United States Patent Office

Des. 192,434

Patented Mar. 20, 1962

192,434

SHARPENER

Paul O. Rawson, Jr., Trumbull, Conn., and Frank M. Grunwald, Syracuse, N.Y., assignors to General Electric Company, a corporation of New York

Filed Dec. 9, 1960, Ser. No. 63,184

Term of patent 14 years

(Cl. D37—1)

Fig. 2.

Fig. 3.

Fig. 4.

Fig. 5.

FIG. 1 is a front perspective view of a sharpener embodying our design;

FIG. 2 is a top plan view of the sharpener;

FIG. 3 is a front elevation view of the sharpener;

FIG. 4 is a side elevation view of the sharpener; and

FIG. 5 is a rear perspective view of the sharpener. The dominant features of the design reside in the portions shown in full lines.

We claim:

The ornamental design for a sharpener, substantially as shown and described.
